CLAIM

The ornamental design for a light-emitting diode, as shown and described here.

DESCRIPTION

FIG. 1 is a perspective view of the light-emitting diode in accordance with my new design, showing an upper surface and side surfaces as viewed from diagonally above;

FIG. 2 is a perspective view thereof, showing a bottom surface and side surfaces as viewed from diagonally above;

FIG. 3 is a front elevation view, the rear elevation view being a mirror image thereof;

FIG. 4 is a top plan view thereof;

FIG. 5 is a bottom plan view thereof;

FIG. 6 is a left side view thereof; and,

FIG. 7 is a right side view thereof.
